UNITED STATES PATENT OFFICE

JAMES J. HENNESSY, OF NEW YORK, N. Y.

JOURNAL LUBRICATOR

Application filed June 11, 1930. Serial No. 460,327.

My invention relates to railway rolling stock and consists in a novel lubricator for an axle journal box.

The main object of my invention is to provide an economical lubricator device adapted to use the continual reciprocation of the journal in the journal box as a motor force for carrying an oil soaked swab from an oil pool in the bottom of the box to the surface 5 of the journal, gravity being resorted to return the swab to the oil pool.

Another object of my invention is to provide a framework for my device resting in the oil reservoir or bottom of the journal box and adapted in conjunction with plates for holding it in position to keep the waste 15 in the rest of the reservoir out of my lubricating mechanism.

Another object of my invention is to provide a lost motion device in my lubricating mechanism whereby an excess movement of the journal is prevented from injuring the lubricating mechanism.

Additional objects will appear in the following specification and accompanying drawing which illustrates a selected embodiment of my invention—

Figure 1 is a vertical section taken on the longitudinal center line of a journal box 30 equipped with my device.

Figure 2 is a horizontal section taken on the line 2—2 of Figure 1.

Figure 3 is a transverse vertical section taken on the line 3—3 of Figure 1.

The body of the box corresponds to the A. R. A. box in general use and has the usual lug 1 at the top of the box positioning the key 2, bearing plate 3 and brass 4 mounted on journal 5, these elements being held in lateral alignment by the usual means.

Under the journal 5 and extending longitudinally of the journal is a frame member having a long narrow portion 8 and a wider portion 9 at the end of portion 8. The portion 9 is open at the top and bottom and is adapted to be placed under the center of the journal 5 within the oil reservoir formed by the lower portion of the journal box, the long portion 8 extending outwardly therefrom.

At the sides of portion 9 are ledges 10, upon which flat springs 11 are mounted. Telescoping the portion 9 and yieldingly supported on the ledges 10 is an upper conduit member 12 which is kept in contact with the journal by means of the springs 11.

Holding the frame 8—9 in position in the journal box and assisting the frame member in keeping the waste out of the lubricating mechanism are holding plates 13 fitting over portion 8 and around portion 9 and member 12.

My lubricating mechanism is mounted in the frame member 8—9. In the portion 9, normally resting on the bottom of the journal box, which serves as an oil reservoir, is a swab 15 of felt or similar material. The outer end of portion 8 is open and pivotally mounts the bell crank 16, the upper arm of which is composed of two sections 18 and 19 hinged together at 20 to permit an outward folding of the sections 18 and 19 from the position shown but not an inward folding thereof. A spring 21, mounted on lower section 18 bears against the outer side of section 19 to resist the outward folding of the sections. The upper end of the bell crank engages the outer end of journal 5. The swab 15 is loosely fitted on the end of a lever 22 which is pivoted on the portion 8 at 23. Pivoted on portion 8 so that its ends will extend above the corresponding ends of lever 22 and bell crank 16 is an intermediate lever 24.

The frame member 8—9 and the member 12 are adapted to keep waste packed in the rest of the reservoir away from the lubricating mechanism enclosed therein.

The outward movement of the journal 5 pushes the bell crank on its pivot and thereby raises the outer arm and lowers the inner arm of lever 24 which in turn lowers the outer arm of lever 22 and raises the swab 15 on the inner arm of lever 22 until the swab engages the surface of the journal 5. The lost motion device in the bell crank, comprised of the folding sections 18 and 19 and spring 21, accommodates any further outward movement of the journal 5 after positive contact between the swab and the

journal. As the journal 5 moves inwardly, the weight of the swab 15 causes the same to return to the oil at the bottom of the journal box.

5 The waste is put into the oil reservoir after my lubricating device has been inserted under the journal. The waste rests on the holding plates 13 and is pushed under the journal and around the same, fitting the 10 space between the journal and journal box sides half way up to the top of the journal and distributes oil over the journal surface by capillary attraction in the usual manner. The waste having been inserted, oil is 15 poured into the box to fully cover the lubricating mechanism and it will be unnecessary to repack or reoil the box at such frequent intervals as is required with ordinary packing.

20 Obviously, many modifications in the details of the structure of my device may be made without departing from the spirit of my invention, and I contemplate the exclusive use of such modifications as come within 25 the spirit of my claims.

I claim:

1. In a journal lubricator, a long relatively narrow box-like framework adapted to fit in a railway journal box and vertically 30 beneath the axis of a journal in said box, an oil holding element contained in said framework, a bell crank pivoted on said framework and adapted to engage the end of said journal, and means operatively connecting 35 said bell crank and oil holding element whereby axial movement of said journal in one direction will cause said oil holding element to be raised to engage said journal.

2. In a journal lubricator, a long relatively narrow box-like framework adapted to fit in a railway journal box and vertically 40 beneath the axis of a journal in said box, an oil holding element contained in said framework, a bell crank pivoted on said framework and adapted to engage the end of said journal, and means operatively connecting 45 said bell crank and oil holding element whereby axial movement of said journal in one direction will cause said oil holding element to be raised to engage said journal and upon movement of said journal in another direction the weight of said oil holding element will cause the same to descend from said journal.

55 3. In a journal lubricator, a framework adapted to fit in a railway journal box and under a journal in said box, an oil holding element in said framework, and means operatively engaging said oil holding element and adapted to engage the end of said journal whereby axial movement of said journal in one direction will cause said oil holding element to be raised to engage said journal, there being a lost motion connection in said 60 means adapted to accommodate said axial

motion of said journal after said oil holding element has engaged said journal.

4. In a journal lubricator, a framework adapted to fit in a railway journal box and under a journal in said box, an oil holding element in said framework, a series of operatively connected levers pivoted on said framework and arranged in a line end to end vertically below the axis of said journal, one of said levers at one end of the series being connected to said oil holding element, and another of said levers at the opposite end of the series being a bell crank having an upstanding arm adapted to engage the end of said journal, whereby movement of said journal in one direction will transmit motion through said series of levers to raise said oil holding element to engage said journal.

5. In a journal lubricator, a framework adapted to fit in a railway journal box and under a journal in said box, said framework comprising upper and lower frame elements with vertically alined openings, springs between the two elements adapted to hold said upper element in contact with said journal, an oil holding element in said framework, and means operatively engaging said oil holding element and adapted to operatively engage the end of said journal whereby movement of said journal in one direction will cause said oil holding element to be raised through said openings to engage said journal.

6. In a journal lubricator, a framework adapted to fit in a railway journal box and under a journal in said box, an oil holding element in said framework, a bell crank pivoted on said framework and adapted to engage the end of said journal, and means operatively connecting one arm of said bell crank and oil holding element whereby outward movement of said journal will cause said oil holding element to be raised to engage said journal, the other arm of said bell crank being adapted to engage said journal and comprising two sections hinged together to permit the sections to fold outwardly, but not inwardly, with respect to each other, and a spring secured on one of the sections and engaging the other of the sections and yieldingly holding said section in a predetermined relation, whereby said bell crank may take up any further outward movement of said journal after said oil holding element has engaged said journal.

7. In a journal lubricator, a framework adapted to fit in a railway journal box and under a journal in said box, plates adapted to hold said framework in position in said box, said plates being also adapted to cooperate with said framework to keep out of the interior thereof waste packed in the journal box, an oil conveyor mounted in said framework, and means operatively en-

gaging said oil conveyor and adapted to engage the end of said journal whereby axial movement of said journal in one direction will cause said conveyor to rise from oil in the lower portion of said box and contact with said journal.

8. In combination, a journal box the lower portion of which forms an oil reservoir, a journal, a framework within said reservoir and under said journal and between the planes of the sides of said journal, an oil soaked swab in said framework, a bell crank pivoted on said framework and engaging the end of said journal, and means operatively connecting said bell crank and swab whereby axial movement of said journal in one direction will cause said swab to be raised from the bottom of the box to engage the lower face of said journal and upon movement of said journal in another direction, the weight of said swab will cause the same to descend from said journal to the bottom of the box.

9. In combination, a journal box the lower portion of which forms an oil reservoir, a journal, a framework within said reservoir and under said journal, plates holding said framework in position and cooperating with said framework to keep out of the interior thereof any waste packed in the reservoir, an oil soaked swab in said framework, and means operatively engaging said swab and the end of said journal whereby axial movement of said journal in one direction will cause said swab to be raised to engage said journal.

10. In combination, a journal box the lower portion of which forms an oil reservoir, a journal, a framework within said reservoir and under said journal, an oil soaked swab in said framework, and means operatively engaging said swab and the end of said journal whereby movement of said journal in one direction will cause said swab to be raised to engage said journal, there being a lost motion connection in said means adapted to take up any further motion of said journal in said direction after said swab has engaged said journal.

11. In combination, a journal box the lower portion of which forms an oil reservoir, a journal, a framework within said reservoir and under said journal, an oil soaked swab in said framework, a bell crank pivoted on said framework with one arm adapted to engage the end of said journal, means connecting the other arm of said bell crank and said swab, whereby movement of said journal in one direction will transmit motion through said series of levers to raise said swab to engage said journal, all of said framework, swab and levers being beneath the bottom of said journal except for restricted portions extending upwardly to engage said journal, and a plate extending

over said framework and beneath said journal, and fibrous packing for said journal carried by said plate.

In testimony whereof I hereunto affix my signature this 26th day of May, 1930.

JAMES J. HENNESSY.
